CROSS THREAD LAYING APPARATUS

Leo Schwartz, New York, and Martin S. Mansson, White Plains, N. Y., assignors to Automatic Sewing Equipment Co., Inc., New York, N. Y., a corporation of New York

Application October 30, 1946, Serial No. 706,552

4 Claims. (Cl. 112—100)

1 The present invention is directed to sewing machines of the usual type and more particularly to a modification thereof whereby the machine may be adapted to lay cross threads, that is, to make a serpentine stitch as well as a straight line stitch.

The present invention has among its objects to provide an attachment for a sewing machine which is operable by the same source of power which operates the machine itself and which is capable of superimposing a cross thread upon the ordinary line of stitches formed by the machine.

It is also among the objects of the present invention to provide a special mechanism operated by the sewing machine shaft and to provide a means for oscillating a thread guide with relation to the needle and thereby form a cross thread.

It is further among the objects of the present invention to provide an attachment for a sewing machine which may be readily thrown into operative or inoperative position as desired in order to introduce or eliminate a cross thread.

It is still further among the objects of the present invention to provide a mechanism for laying a cross thread which may be an attachment to an existing sewing machine or be an integral part thereof, which is simple in construction, inexpensive, sturdy and effective in operation and capable of withstanding a long period of use at the normally high speeds of commercial sewing machines.

In practicing the present invention there is provided an ordinary sewing machine mechanism including a needle and instrumentalities usually including a hook or looper which forms stitches in fabric passing through the machine. Such a machine may be of the single needle type or may be a multiple needle machine. There is provided at least one thread guide which is so mounted on the head of the machine or on its bed that it may be oscillated in front of the needle and throw a thread across the path of the stitches made by said needle. As each portion of thread is thrown across the path of the fabric being fed to the needle, it forms a relatively loose loop which is caught by the next stitch and is pinned down. Then as the thread guide reverses its oscillation, it first tightens the thread within the stitch and then throws a loop on the opposite side of the needle which is caught by the next stitch. As this continues, there is formed a sinuous line of said thread or what is commonly termed a cross thread. Ordinarily this thread is distinctive in color and/or in character from the

stitches themselves and from the fabric so that a pleasing and contrasting appearance is provided.

The machine may be so adjusted that the oscillations of the thread guide may be in a number of various ratios to the reciprocations of the needles, thus altering the character of the cross thread formed thereby. Where a plurality of needles are provided in the machine, there may be a corresponding number of oscillating thread guides and the machine be thus adapted for making a plurality of cross threads simultaneously.

Usually the mechanism is operated by the main shaft of the sewing machine and a set of gears is provided at the rear of the sewing machine arm which connects by a suitable shaft and other elements to a link arrangement. The thread guide is mounted generally on the presser foot bar by means of a collar and an extension thereon holds the guide in front of the needle.

In the accompanying drawings constituting a part hereof and in which like reference characters indicate like parts,

25 Fig. 1 is a horizontal cross-sectional view of a device made in accordance with the present invention and adapted for producing cross threads, some parts being shown in elevation;

Fig. 2 is a vertical cross-sectional view taken through the casing containing the bevelled gears and clutch, some parts being shown broken away and other parts in elevation for clearness;

Fig. 3 is a front elevational view looking at the head of the sewing machine; and

35 Fig. 4 is a fragmentary view similar to Fig. 2 showing the clutch in disconnecting position.

The sewing machine is of the usual type and includes a bed 1 on one side of which is a standard 2 with a horizontal arm 3 terminating in head 4. A horizontal shaft 5 extends through arm 3 and has secured thereto an extension piece 6 on which the usual fly-wheel 7 of the sewing machine is mounted. Element 6 is an adapter which allows the mechanism to be placed on a sewing machine previously built.

45 Mounted on element 6 is a gear 8 meshing with idler gear 11 on pivot 12. Said idler may be of non-metallic material in order to provide silent operation. A third gear 13 extending laterally of arm 3 meshes with gear 11. The set of gears is held within a casing 9 secured to the standard of the machine and provided with a removable cover 10 to allow access thereto.

Counter-shaft 14 is mounted on bracket 15 which in turn is secured by set screw 16 or the like along arm 3 of the machine. Bracket 15 has

an extension 17 in the form of a casing which is closed by removable cover 18. On counter-shaft 14 is loosely mounted bevelled gear 19.

The lower end of the casing is formed with a hollow extension 20 with a thrust washer 21 mounted thereon and a stub shaft 22 operates within extension 20. Bevelled gear 23 mounted on the upper end of stub shaft 22 is adapted to mesh with gear 19. Gear 23 may be made of nonmetallic material to provide silent operation. Washer 21 is on shaft 22 between the lower face of gear 23 and the upper face of extension 20.

Sleeve 24 is slidably mounted on counter-shaft 14 and has an operating knob 25 secured thereto. The end of sleeve 24 adjacent to gear 19 is provided with tongues 26 adapted to mesh with corresponding notches 26' in gear 19. A longitudinal slot 27 in sleeve 24 accommodates a pin 28 fixed in shaft 14. This arrangement operates as a clutch so that when knob 25 is at the right as shown in Fig. 4, no motion is transmitted from shaft 14 to shaft 22 and when knob 25 is pushed to the left as shown in Fig. 2, the sets of notches and tongues will mesh and gear 19 will drive shaft 22.

At the lower end of shaft 22 is a collar 29 carrying extension 30, said collar carrying counter-weight 31 opposite extension 30. Link 32 has one end eccentrically mounted at 33 on extension 30.

Presser-foot bar 34 operates within bushing 35 in head 4 of the sewing machine. A collar 36 is fitted loosely around said bushing and a collar bearing 37 is fixed to bar 34 by set screw 38. Presser-foot 39 is secured to bar 34 below the same.

An angular connector 40 integral with or fixed to collar 36 has a bent arm 41 extending in front of the sewing machine instrumentalities. As shown in Fig. 1, it has a pair of tubular guides 42 and 43 secured within the same, said tubes extending down in front of the needles 44 and close to the bed 1 of the machine. Said needles are mounted as usual on needle bars 45.

An extension 46 integral with collar 36 provides a pivot 47 to which the free end of link 32 is secured. In order to provide a thread guide there is mounted at 49 on the top of arm 3, an angular rod 48 having a pair of openings 50 therein. Thread 51 from a suitable source passes through said guide openings 50 and through guides 42 and 43 in front of the needles.

In the operation of the device knob 25 is moved to the left and the machine is started. As fabric is fed through the machine needles 44 make the usual stitches therein. By action of extension 30, link 32, extension 46 and connector 40, guides 42 and 43 are caused to oscillate from one side of their respective needles to the other side. As such motions take place, the thread 51 being fed through the guides is pinned by the stitches. Thereby a cross thread is formed.

Although the invention has been described setting forth a single embodiment of the invention, many changes in the details of the construction may be made within the spirit of the invention. For instance, usually there is one oscillation of a thread guide for two reciprocations of the needle so that one cross thread is formed for every two aligned stitches. However, this ratio may be changed and there may be a cross thread for every straight stitch or there may be one cross stitch for any reasonable number of straight stitches. By so doing the pitch of the cross stitch may be altered at will. While two needles are illustrated, the machine is capable of operating

with any of the usual number of needles provided in sewing machines. Also the cross stitch may be caused to loop through two or more parallel stitches instead of a single line of stitches.

The clutch illustrated in the drawings may be changed to an entirely different type of mechanism for throwing the cross stitch mechanism in or out. Also the clutch may be entirely omitted and the machine operate continually with a cross stitch. The drive of the cross thread mechanism may be altered so that the power is taken from the looper shaft rather than from the main shaft. In such case, the bracket 15 may be omitted and casing 17 or its equivalent may be mounted on bed 1.

From the above, it will be apparent that numerous variations in the details of the mechanism may be made within the principles herein set forth and therefore the invention is to be broadly construed and not to be limited except by the character of the claims appended hereto.

We claim:

1. In a cross thread laying machine having a bed, an overhanging arm thereon, a head at the free end of said arm, a needle, a needle bar carrying said needle, said needle bar being mounted in said head and means for reciprocating the same to form stitches in fabric, a thread guide in front of said needle and adjacent thereto, a presser-foot bar mounted in said head rearwardly of said needle, the improvement which comprises an angular connector pivoted on said presser bar for horizontal movement, said guide being secured to said connector, a rearward extension on said connector, a link pivoted at one end to said extension and at the other end to a second extension, a collar on which said second extension is mounted, a counterweight on said collar opposite to said second extension, a box having gearing connected to said collar, and driving means for horizontally rotating said second extension to cause oscillation of said connector about said presser bar as a center and a clutch mounted on said box for coupling the gearing therein to said driving means to rotate said second extension.

2. In a cross thread laying machine having a bed, an overhanging arm thereon, a head at the free end of said arm, a needle, a needle bar carrying said needle, said needle bar being mounted in said head and means including a horizontal main shaft in said arm for reciprocating the same to form stitches in fabric, a thread guide in front of said needle and adjacent thereto, a presser-foot bar mounted in said head rearwardly of said needle, the improvement which comprises an angular connector pivoted on said presser bar for horizontal movement, said guide being secured to said connector, a rearward extension on said connector, a link pivoted at one end to said extension and at the other end to a second extension, and means for horizontally rotating said second extension to cause oscillation of said connector about said presser bar as a center from side to side and across the front of said needle, a box containing a pair of meshing gears on the side of said arm, a vertical shaft connected to one of said gears extending downwardly therefrom and connected to said second extension, a counter-shaft parallel to and driven by said main shaft and disposed adjacent to the side of said arm, said counter-shaft loosely mounting the second gear and a clutch mounted on said box for coupling said second gear therein to said counter-shaft to rotate said extension.

3. In a cross thread laying machine having a bed, an overhanging arm thereon, a head at the free end of said arm, a needle, a needle bar carrying said needle, said needle bar being mounted in said head and means including a horizontal main shaft in said arm for reciprocating the same to form stitches in fabric, a thread guide in front of said needle and adjacent thereto, a presser-foot bar mounted in said head rearwardly of said needle, the improvement which comprises an angular connector pivoted on said presser bar for horizontal movement, said guide being secured to said connector, a rearward extension on said connector, a link pivoted at one end to said extension and at the other end to a second extension, and means for horizontally rotating said second extension to cause oscillation of said connector about said presser bar as a center from side to side and across the front of said needle, a box containing a pair of meshing gears on the side of said arm, a vertical shaft connected to one of said gears extending downwardly therefrom and connected to said second extension, a counter-shaft parallel to and driven by said main shaft and disposed adjacent to the side of said arm, said counter-shaft loosely mounting the second gear, said main shaft extending out of the rear of said arm, an extension piece on the end of said main shaft, gearing on said piece and connected with said counter-shaft and a clutch mounted on said box for coupling said second gear therein to said counter-shaft to rotate said extension.

4. In a cross thread laying machine having a bed, an overhanging arm thereon, a head at the free end of said arm, a needle, a needle bar carrying said needle, said needle bar being mounted in said head and means including a horizontal main shaft in said arm for reciprocating the same to form stitches in fabric, a thread guide in front of said needle and adjacent thereto, a presser-

foot bar mounted in said head rearwardly of said needle, the improvement which comprises an angular connector pivoted on said presser bar for horizontal movement, said guide being secured to said connector, a rearward extension on said connector, a link pivoted at one end to said extension and at the other end to a second extension, and means for horizontally rotating said extension to cause oscillation of said connector about said presser bar as a center from side to side and across the front of said needle, a box containing a pair of meshing gears on the side of said arm, a vertical shaft connected to one of said gears extending downwardly therefrom and connected to said second extension, a counter-shaft parallel to and driven by said main shaft and disposed adjacent to the side of said arm, said counter-shaft loosely mounting the second gear, said main shaft extending out of the rear of said arm, a gear casing secured to said arm and containing the ends of said main and counter-shafts, and a set of gears in said casing connecting said shafts and a clutch mounted on said box for coupling said second gear therein to said counter-shaft to rotate said extension.
